(57) **CLAIM**

The ornamental design for an electric bed, as shown and described.

DESCRIPTION

FIG. 1 is a perspective view of an electric bed, showing the new design;

FIG. 2 is another perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the electric bed and form no part of the claimed design. The dot-dash lines shown in FIGS. 1-2 and 5-8 define the bounds of the claimed design and form no part of the claimed design.

1 Claim, 6 Drawing Sheets
